(57) **CLAIM**

The ornamental design for a display screen or a portion thereof with graphical user interface, as shown and described.

DESCRIPTION

FIG. 1 is a front view of a first embodiment of the display screen or a portion thereof with graphical user interface, showing our new design; and,

FIG. 2 is a front view of a second embodiment of the display screen or a portion thereof with graphical user interface. In the reproduction, the broken lines forms a part of the claim. The outermost solid line represents the display screen and forms a portion of the claim.
